QUATERNARY AMMONIUM COMPOUNDS

William S. Gump, Montclair, N. J., assignor to Burton T. Bush, Inc., New York, N. Y., a corporation of New Jersey

No Drawing. Application February 29, 1944,
Serial No. 524,463

5 Claims. (Cl. 260—567.6)

1

This invention relates to new quaternary ammonium compounds and to a process for making them.

An object of this invention is to provide new quaternary ammonium compounds possessing desirable bactericidal properties. A further object is a simple and efficient process for making such compounds. Other objects will appear to those skilled in the art from the following description.

These objects are accomplished by providing a series of new quaternary ammonium compounds, which may be represented by the following general formula:

wherein R_1 , R_2 , and R_3 are lower alkyl radicals; R_4 is a higher molecular aliphatic radical, preferably containing 8 to 18 carbon atoms; An represents an anion selected from the group consisting of anions of inorganic and organic acids; and Ar represents an arylene or substituted arylene radical and may be attached to the

2

5

radicals in either the ortho, meta, or para positions. Substitution in the arylene radical may be in any available position and may be effected, for example, by alkyl or halogen radicals, or both.

The new quaternary ammonium compounds are made by a process which involves treating an ether having the following general formula:

15

wherein R_1 , R_2 , R_3 and Ar have the same significance as above, with a stoichiometrical amount of

20 inorganic or organic acids or alkyl esters of polybasic inorganic acids, at elevated temperatures, and, if desired, in the presence of inert solvents.

As exemplifying specific ethers which may be employed in this invention, the following may be 25 mentioned:

Name of Ether	Chemical Formula	Boiling Range, ° C.
4-N,N-dimethylaminobenzyl-n-dodecyl.....	$C_{12}H_{25}-O-CH_2-\text{C}_6\text{H}_4-N(CH_3)_2$	210°-212° at 4 mm. Hg.
2-methyl-5-N,N-dimethylaminobenzyl-n-dodecyl.....	$C_{12}H_{25}-O-CH_2-\text{C}_6\text{H}_4-\text{CH}_3-N(CH_3)_2$	205°-207° at 4 mm. Hg.
4-N,N-dimethylaminobenzyl-n-tetradecyl.....	$C_{14}H_{29}-O-CH_2-\text{C}_6\text{H}_4-N(CH_3)_2$	210°-212° at 4 mm. Hg.
4-N,N-diethylaminobenzyl-n-dodecyl.....	$C_{12}H_{25}-O-CH_2-\text{C}_6\text{H}_4-N(C_2H_5)_2$	225°-230° at 5-6 mm. Hg.
3-methyl-4-N,N-dimethylaminobenzyl-n-dodecyl.....	$C_{12}H_{25}-O-CH_2-\text{C}_6\text{H}_4-\text{CH}_3-N(CH_3)_2$	207°-210° at 4-5 mm. Hg.
2-methyl-4-N,N-dimethylaminobenzyl-n-dodecyl.....	$C_{12}H_{25}-O-CH_2-\text{C}_6\text{H}_4-\text{CH}_3-N(CH_3)_2$	222°-226° at 5-6 mm. Hg.
2-methyl-5-N,N-dimethylaminobenzyl-2-ethyl-n-hexyl.....	$C_6H_{13}-O-CH_2-\text{C}_6\text{H}_4-\text{CH}_3-N(CH_3)_2$	152°-155° at 4 mm. Hg.

Name of Ether	Chemical Formula	Boiling Range, ° C.
2-methyl-6-N,N-dimethylaminobenzyl-n-octyl.....		175°-180° at 6 mm. Hg.
2-methyl-6-N,N-dimethylaminobenzyl-n-decyl.....		183°-185° at 5 mm. Hg.
2-methyl-6-N,N-dimethylaminobenzyl-n-tetradecyl.....		235°-236° at 6 mm. Hg.
2-methyl-4-N,N-diethylaminobenzyl-n-dodecyl.....		229°-233° at 4 mm. Hg.
3-chloro-6-N,N-dimethylaminobenzyl-n-dodecyl.....		228°-233° at 4 mm. Hg.
3-chloro-4-N,N-dimethylaminobenzyl-n-decyl.....		203°-208° at 4 mm. Hg.
3-chloro-4-N,N-dimethylaminobenzyl-n-dodecyl.....		220°-225° at 4 mm. Hg.
3-chloro-4-N,N-dimethylaminobenzyl-n-hexadecyl.....		240°-245° at 4 mm. Hg.
3-bromo-6-N,N-dimethylaminobenzyl-n-dodecyl.....		216°-220° at 4 mm. Hg.

All of the foregoing ethers are yellow, viscous oils and may be made by effecting a reaction between an aromatic tertiary amine and formaldehyde and converting the resulting tertiary amine-substituted benzyl alcohol into its corresponding ether by reacting an alkali metal salt of the alcohol with a long chain alkyl halide.

As agents which will form quaternary ammonium compounds when treated with the foregoing ethers the following are mentioned: dimethyl sulfate, diethyl sulfate, ethyl bromide and methyl iodide.

This invention is illustrated by the following examples without however limiting the invention to them.

EXAMPLE 1

Preparation of 4-N,N-dimethylamino benzyl alcohol

A mixture of 336 grams N,N-dimethyl aniline, 450 grams concentrated hydrochloric acid (Sp. G=1.19) and 1350 grams aqueous formaldehyde (39%) were kept at 37° C. for 48 hours. The mixture was then cooled in an ice bath and 900 grams crushed ice added. A cold (5° C.) solution of 300 grams of sodium hydroxide in 400 grams of water is added in small portions under stirring so that the temperature did not rise above 0° C. The oil was then extracted from the

50 mixture with 500 grams of isopropyl ether and washed three times, each time with 200 grams of water. The isopropyl ether solution was dried with anhydrous calcium chloride, filtered and distilled. After removal of the isopropyl ether, vacuum fractionation at 3 mm. pressure yielded the following distillates:

55	Fraction	Boiling Range, ° C.	Yield, grams
I.....		60-75	184 (unchanged N,N-dimethylaniline).
II.....		75-133	22.
III.....		133-136	92.
IV.....		136-160	6.

60 The residue, consisting mainly of 4,4'-tetramethylamino diphenylmethane, weighed 28 grams. Fraction III represented the desired 4-N,N-dimethylamino benzyl alcohol.

Preparation of 4-N,N-dimethylaminobenzyl-n-dodecyl ether

9.2 grams of sodium were cut into small, thin pieces and added to 92 grams of xylene which had been dried over sodium. The mixture was well stirred and heated to reflux temperature; 88 grams of 4-N,N-dimethylamino benzyl alcohol were then dropped in during one hour. Approximately another hour of refluxing was needed un-

til the sodium had all gone into solution and the sodium salt of the benzyl alcohol had formed. 82 grams of lauryl chloride were then added and refluxing and stirring continued for two hours. The mixture was then poured into 400 grams of water, the oil layer separated and dried with anhydrous potassium carbonate. After the xylene was driven off by distillation the residue was fractionated at 4 mm. of mercury pressure. The following fractions were collected:

Fraction	Boiling Range, °C.	Yield, grams
I.....	90-120	44
II.....	120-210	40
III.....	210-212	66

Fractions I and II consist of the unchanged alcohol and lauryl chloride. Fraction III represents the desired 4-N,N-dimethylaminobenzyl-n-dodecyl ether in a yield of 92% of the theory, taking into account the recovered 4-N,N-dimethylaminobenzyl alcohol and lauryl chloride.

This novel ether, 4-N,N-dimethylaminobenzyl-n-dodecyl ether, is a yellowish, viscous oil, having a boiling point of 210°-212° C. at 4 mm. of mercury pressure.

Preparation of 4-trimethylammonium benzyl-n-dodecyl ether methosulfate

30 grams of dimethyl sulfate are dropped into 64 grams of 4-N,N-dimethylaminobenzyl-n-dodecyl ether over a period of 30 minutes and at room temperature (25° C.). The mixture immediately becomes hot and the color becomes first green and then yellow. The mixture is heated on the steam bath for one hour and then allowed to cool to room temperature. There is thus formed a water-soluble mass of the consistency of crystalline wax. Two crystallizations from dioxane result in white, soft crystals, melting at 93°-94° C. The yield is 72 grams or 80% of theory.

4-trimethylammonium benzyl-n-dodecyl ether methosulfate, when tested according to the U. S. Food and Drug Administration method (Circular 198, December 1931) kills *Eberthella typhi* and *Staphylococcus aureus* in ten minutes at 20° C. in concentrations of 1:15000 to 1:25000.

EXAMPLE 2

Preparation of 2-methyl-5-N,N-dimethylamino benzyl alcohol

A mixture of 200 grams N,N-dimethyl-p-toluidine, 200 grams concentrated hydrochloric acid (Sp. G.=1.19) and 600 grams aqueous formaldehyde (38%) is kept on the steam bath for 24 hours. The solution is allowed to cool to about 25° C. and is made alkaline by the slow addition of 700 grams of 20% aqueous sodium hydroxide under cooling. The oil which separates is extracted from the mixture with 300 grams of isopropyl ether. The isopropyl ether solution is washed three times with water, 150 grams of water being used for each wash, and then dried by means of anhydrous potassium carbonate. The isopropyl ether is distilled off and the residue fractionated under a pressure of 5 mm. of mercury. 24 grams, consisting mostly of unchanged dimethyl-p-toluidine are collected up to 90° C.; a mixed fraction (11 grams) is distilled from 90° to 110° C.; and at 110° to 111° C., 109 grams of 2-methyl-5-N,N-dimethylamino benzyl alcohol are obtained.

Preparation of 2-methyl-5-N,N-dimethylamino benzyl-n-dodecyl-ether

11.5 grams of sodium were cut into small, thin pieces and added to 115 grams of xylene, dried over sodium. The mixture was well stirred and heated. At reflux temperature, 132 grams of 2-methyl-5-N,N-dimethylamino benzyl alcohol were dropped in during one hour. Refluxing was continued for about another hour until all the sodium had disappeared and the sodium salt of the benzyl alcohol derivative was formed. 102 grams of lauryl chloride were then added and stirring and refluxing continued for two hours. The mixture was then poured into 500 grams of water, the oil layer separated and dried with anhydrous potassium carbonate. After the xylene was driven off, the residual oil was distilled at a pressure of 4 mm. of mercury and the following fractions collected:

Fraction	Boiling Range, °C.	Yield, grams
I.....	Up to 140	64
II.....	140-200	9.5
III.....	205-207	123

Fraction I consists of unchanged 2-methyl-5-N,N-dimethylamino benzyl alcohol and lauryl chloride; and fraction III represents the desired ether in a yield of 87% of the theory.

This novel ether, 2-methyl-5-N,N-dimethylamino-benzyl-n-dodecyl ether, is a yellowish, viscous oil, having a boiling point of 205°-207° at 4 mm. of mercury pressure.

Preparation of 2-methyl-5-trimethylammonium benzyl-n-dodecyl ether methosulfate

A mixture of 44.4 grams of 2-methyl-5-N,N-dimethylamino benzyl-n-dodecyl ether, 20 grams of dimethyl sulfate and 34 cc. of benzene are refluxed in an oil bath at 120° C. for 4 hours, under atmospheric pressure. The benzene and excess dimethyl sulfate are then distilled under reduced pressure (100 mm. Hg). The residue (62 grams) was washed with 150 grams of petroleum ether and again freed from remaining solvent by heating in vacuo. After recrystallization from dioxane the quaternary salt is obtained in the form of white, soft, thin platelets melting at 130.5°-132° C. A second crystallization from dioxane yields crystals melting at 132°-133° C.

2-methyl-5-trimethylammonium benzyl-n-dodecyl ether methosulfate, when tested according to the U. S. Food and Drug Administration method (Circular 198, December 1931), kills (a) *Eberthella typhi* in a concentration of 1:25000 to 1:35000 and (b) *Staphylococcus aureus* in a concentration of 1:20000 to 1:30000, when exposed at 20° C. for ten minutes.

EXAMPLE 3

Preparation of 2-methyl-4-N,N-dimethylamino benzyl alcohol

A mixture of 84 grams N,N-dimethyl-m-toluidine, 120 grams concentrated hydrochloric acid (Sp. G.=1.19) and 500 grams aqueous formaldehyde (38% solution) was kept at room temperature for 44 hours. The mixture was cooled in an ice bath and made just alkaline to litmus paper by the slow addition of sufficient 20% sodium hydroxide solution. The oil formed was extracted from the mixture with 300 grams of isopropyl ether. The isopropyl ether solution was washed with water and dried by means of

anhydrous potassium carbonate. The isopropyl ether was distilled off and the residue distilled in vacuo (5-6 mm. of mercury pressure). The following fractions were collected:

Fraction	Boiling Range, °C.	Yield, grams
I	120-135	2.5
II	143-148	23
III	148-165	13.5
Residue		37

Fraction II consisted of the desired 2-methyl-4-N,N-dimethylamino benzyl alcohol.

Preparation of 2-methyl-4-N,N-dimethylamino benzyl-n-dodecyl ether

2.3 grams of sodium were cut into small, thin pieces and added to 23 grams of xylene, dried over sodium. The mixture was stirred and heated to reflux temperature. 23 grams of 2-methyl-4-N,N-dimethylamino benzyl alcohol were then dropped in during one hour. After the sodium had gone into solution, 25 grams of lauryl bromide were added and stirring and refluxing continued for two hours. The mixture was then poured into 300 grams of water, the oil separated and dried by means of anhydrous potassium carbonate. Xylene was removed by distillation under diminished pressure and the residue was fractionated at a pressure of 5-6 mm. of mercury. 21 grams distilled from 80°-210°; at 225°-230°, 11 grams of the 2-methyl-4-N,N-dimethylaminobenzyl-n-dodecyl ether were collected.

This ether is a light yellow, viscous liquid which may be used as a solvent, plasticizer and intermediate for organic compounds.

Preparation of 2-methyl-4-trimethylammonium benzyl dodecyl ether methosulfate

6.4 grams of 2-methyl-4-dimethylaminobenzyl dodecyl ether, 3 grams of dimethyl sulfate and 3 c. c. of benzene were heated on the steam bath for 2 hours. The benzene and excess dimethyl sulfate were then removed by heating the viscous oil to about 100° C. and applying diminished pressure, using finally a vacuum of 4 mm. of mercury. The residue was then washed with 30 grams of petroleum ether and again dried in vacuo. 8 grams of a light-tan colored, waxy substance remained which was clearly soluble in water. This is 2-methyl-4-trimethylammonium benzyl dodecyl ether methosulfate.

This material, when tested at 20° C. for ten minutes according to the U. S. Food and Drug Administration method (Circular 198, December, 1931), kills *Eberthella typhi* in concentrations of 1:15000 to 1:25000. In similar manner, the following quaternary salts were prepared:

- 4-dimethyl ethylammonium benzyl-n-dodecyl ether methosulfate
- 4-trimethylammonium benzyl-n-tetradecyl ether methosulfate
- 4-diethyl-methylammonium benzyl-n-dodecyl ether methosulfate
- 3-methyl-4-trimethylammonium benzyl-n-dodecyl ether methosulfate
- 2-methyl-5-trimethylammonium benzyl-2-ethyl-n-hexyl ether methosulfate
- 2-methyl-5-trimethylammonium benzyl-n-octyl ether methosulfate
- 2-methyl-5-trimethylammonium benzyl-n-decyl ether methosulfate

- 2-methyl-5-trimethylammonium benzyl-n-tetradecyl ether methosulfate
- 2-methyl-4-diethyl-methylammonium benzyl-n-dodecyl ether methosulfate
- 3-chloro-6-trimethylammonium benzyl-n-dodecyl ether methosulfate
- 3-chloro-4-trimethylammonium benzyl-n-decyl ether methosulfate
- 3-chloro-4-trimethylammonium benzyl-n-dodecyl ether methosulfate
- 3-chloro-4-trimethylammonium benzyl-n-hexadecyl ether methosulfate
- 3-bromo-6-trimethylammonium benzyl-n-dodecyl ether methosulfate

- 15 The foregoing quaternary ammonium compounds, as first isolated, are viscous oils or waxes, of yellowish or brownish color. After crystallization attempts, using a suitable solvent, as, for example, dioxane, some of the compounds retain their oily or waxy characteristics, whereas others form crystalline solids. All, however, are quite soluble in water whether in the form as first isolated or after crystallization attempts as just noted; and all likewise possess desirable bactericidal properties.
- 20
- 25

The foregoing illustrates the practice of my invention which, however, is not to be limited thereby but is to be construed and limited solely by the appended claims.

- 30 I claim:
- 1. New quaternary ammonium compounds having the general formula:

wherein R₁, R₂ and R₃ are lower alkyl radicals; Ar represents an anion selected from the group consisting of anions of inorganic and organic acids; Ar is a member selected from the group consisting of arylene, halogen-substituted arylene and alkyl-substituted arylene radicals; and R₄ is an alkyl radical having 8 to 18 carbon atoms.

- 2. New quaternary ammonium compounds having the general formula:

50 wherein R₄ is an alkyl radical having 8 to 18 carbon atoms.

- 3. As a new compound, 4-trimethylammonium benzyl-n-dodecyl ether methosulfate.
- 4. As a new compound, 2-methyl-5-trimethylammonium benzyl-n-dodecyl ether methosulfate.
- 5. As a new compound 2-methyl-4-trimethylammonium benzyl-n-dodecyl ether methosulfate.

WILLIAM S. GUMP.
